KERF-CUTTING MINING MACHINE

Thomas E. Pray, Chicago, Ill., assignor to Goodman Manufacturing Company, Chicago, Ill., a corporation of Illinois

Application October 25, 1940, Serial No. 362,743

6 Claims. (Cl. 262—28)

This invention relates to improvements in kerf-cutting mining machines, and more particularly to track mounted machines adapted to cut and clean dirt bands from coal seams.

The principal object of my invention is to provide an improved and simplified construction in which the overall height can be reduced to a minimum without sacrificing strength and adjustability required in machines of the character described.

A machine of the present invention employs many of the features of the machine disclosed in my prior Patent No. 2,082,119, issued June 1, 1937, but affords a reduction in vertical height and increased efficiency of operation by a rearrangement of the turntable mechanism for swinging the cutter bar horizontally to make an arcuate cut.

The invention may best be understood by reference to the accompanying drawings, in which:

Figure 1 is a plan view of a machine constructed in accordance with my invention;

Figure 2 is an enlarged vertical section of the front end of the machine, taken generally on the longitudinal center line thereof;

Figure 3 is a plan view of the part of the machine shown in Figure 2, with parts broken away to show certain details of construction;

Figure 4 is an enlarged detail section taken generally through the cutter bar and looking rearwardly toward the back of the machine;

Figure 5 is a detail section taken on line 5—5 of Figure 2;

Figure 6 is a detail section taken on line 6—6 of Figure 2, and drawn to a slightly smaller scale than Figures 4 and 5;

Figure 7 is a detail section taken on line 7—7 of Figure 2; and

Figure 8 is a detail section taken on line 8—8 of Figure 3.

Referring now to details of the embodiment of my invention illustrated in the drawings, the machine generally comprises a wheeled truck 10 adapted to travel on the mine floor and forming a base frame on which is mounted a pair of upright frame members 12, 12 spaced apart and supporting between them a cutting element 13 including a frame 14, a motor 15 secured to the rear of said frame, and a turntable 11 at the front of said frame having a pair of parallel spaced horizontally disposed cutter bars 16 and 17 mounted thereon for lateral swinging movement across the front end of the machine. Cutter

chains 18 and 19 of the usual form are carried by the cutter bars 16 and 17, respectively.

The wheeled truck 10 includes a relatively flat base member 21 having depending front wheel supports 22, 22 with track wheels 23, 23 thereon and similar rear wheel supports with track wheels 25, 25 thereon. The wheel supports on opposite sides of the frame are separated so as to leave a central space for a slack conveyer 26 extending longitudinally of the machine beneath the base member 21 for carrying away the cuttings discharged from the cutter bars, as will hereinafter more fully appear.

Referring now to the construction and arrangement of the turntable 11 thereof, which comprises one of the principal features of my invention, said turntable consists of a hollow, generally cylindrical, member 30, open at top and bottom, and having an annular base 32 rotatably mounted on an open annular bearing plate 33 projecting at the front end of the frame 14. The turntable is secured to said bearing plate by a retaining ring 34 bolted to the bottom of said base, as seen in Figure 2. A horizontal arcuately-shaped gear member 28 is connected with the upper margin of the cylindrical member 30 and surrounds the latter excepting at the front thereof where the upper part of said cylindrical member 30 is extended forwardly to form a trough-like support 35. Said support has a bottom wall 36 with an elevated central portion 36a to which the rear ends of the cutter bars 16 and 17 are secured, as by bolts 31, 31. The support 35 also has upright side walls 37, 37 which extend rearwardly to merge with the curved rear wall 38 of the cylindrical member 30. The bottom wall 36, together with the adjacent side walls 37, 37, form in effect channels at opposite sides of the cutter bars 16 and 17, which channels extend to the open cylindrical portion of the member 30.

In the form shown herein, the gear member 28 is connected around the side walls 37, 37 and rear wall 38 of the cylindrical member 30 by two depending flanges 39 and 39a. The inner flange 39 is curved downwardly into abutting engagement with the upper margins of the walls 37 and 38 of the cylindrical member 30, while the flange 39a is formed in spaced relation with the inner flange 39 and has an in-turned foot 39b which rests on an outwardly projecting ledge 39c formed integrally with the walls 37 and 38. The flanged arrangement just described forms in effect a generally tubular reinforcing member extending around the top of the cylindrical member 30 and

projecting forwardly therefrom to the front end of the projecting support 35, as shown in Figure 3.

An extension chute 40 is telescopically mounted in one of the channels beneath one side of the lower cutter bar 17. As herein shown, said chute is disposed on the left-hand channel since the cutter chains 18 and 19 are usually driven in a counter-clockwise direction. Should the chains be driven in the opposite direction, the chute 40 would be disposed on the right side of the cutter bars. The chute 40 has an extended upright outer wall 41, and is arranged to be extended forwardly into endwise engagement with the mine wall beneath the kerf to catch the cuttings as they are brought rearwardly by the cutter chains.

The front end of chute 40 is supported by a horizontal plate 42, which extends laterally beneath the cutter bars 16 and 17 and is secured by an upright bolt 43 to a roller frame 44. Said roller frame is guided for movement along a longitudinal slot 45 formed centrally of said cutter bars (see Figure 4). It has a pair of rollers 46, 46 on transversely disposed stub shafts 47, 47 at opposite sides thereof, adapted to have rolling engagement between the upper and lower cutter bars. A pair of rollers 48, 48 are also mounted on the upright bolt 43, above and below the roller frame 44 so as to have rolling engagement between the opposed inner sides of each of the cutter bars 16 and 17. A yoke 49 is mounted at the top of the bolt 43, with its ends in sliding engagement with the upper surface of the upper cutter bar 16. The roller support just described supports the laterally offset front end of the chute when it is extended beyond the support 35 of the turntable.

A horizontally extended shoe 50 is pivotally supported beneath the front end of chute 40 and arranged to have sliding engagement with the working face of the mine wall when the machine is in cutting position, as indicated in Figure 2. Means are also provided for yieldably urging the chute forwardly and maintaining it in engagement with the mine wall, comprising a cable 51 connected at one end to an abutment 52 at one side of the chute. Said cable is trained over a sheave 53 mounted near the front of the support 35 and thence rearwardly where it is connected to an elongated coil spring 54 in a housing 55 mounted along the side of the support 35, as shown in Figure 3. The spring 54 is normally under tension to maintain the chute in yielding contact with the working face at varying degrees of penetration of the cutter bars.

The cutter chains 18 and 19 are driven from the motor 15 on main frame 14, as follows: An armature pinion 56 is meshed with a spur gear 56a on a longitudinal shaft 57. The latter shaft extends forwardly and has a bevel pinion 58 keyed on its forward end. Said bevel pinion meshes with a bevel gear 59 keyed on an upright shaft 60. The bevel gears just mentioned are supported on suitable ball bearings in a bearing support 67 forming part of the frame 14 but projecting forwardly beneath the open cylindrical member 30. Said bearing support has a cover plate 61 secured thereto. An outer bearing support 62 projects upwardly from said cover plate and extends into a bearing member 63 supported on a horizontal web 64, projecting rearwardly from the front wall of the cylindrical member 30, as shown in Figure 2. The bearing member 63 has a skirt 66 around its sides and rear so as to assist in directing the cuttings out-

wardly around the cover plate 61, and into a hopper 65, disposed beneath the forwardly projecting portion 67 of frame 14.

The cover plate 61 also has an upright inner bearing support 68 detachably mounted thereon, which surrounds the shaft 60. The latter shaft has a cap 69 formed integral with its upper end extending into driving engagement with a sleeve 70, which is journaled on suitable ball bearings for rotation about the upper end of the inner bearing support 68. A pair of driving sprockets 71 and 72 are secured in spaced relation along the sleeve 70 to drive the cutter chains 18 and 19 of cutter bars 16 and 17, respectively.

With the construction just described, the cuttings from the kerf will be collected on chute 40 and brought rearwardly by the cutter chains, through the support 35, and discharged into the cylindrical member 30, where they will be dropped through the openings on opposite sides of the cover plate 61 into the hopper 65. The cutter chains can be driven at any position of adjustment of the turntable 11 relative to the frame 14.

The hopper 65 is arranged to discharge through bottom opening 75 into the conveyor 26 mounted longitudinally beneath the main frame member 21 of the machine, as has been previously mentioned. This conveyer may be of any type, as herein shown consisting of a flight conveyer comprising a pair of endless chains 76 having flights 77 carried therebetween riding along and under a pan 78. The rear end of the conveyer can be arranged in any suitable manner for discharging the cuttings to the rear of the machine, as for instance as shown in my Patent No. 2,082,119, previously mentioned, in which the conveyer 26 discharges into a second conveyer 79 mounted for lateral swinging and vertical elevating movement relative to the first conveyer. The arrangement for final discharge of the conveyer 26 forms no part of the present invention so need not be described in detail herein.

The gearing for raising and lowering the cutter mechanism 13 as a whole relative to the base frame and for swinging the turntable, is disposed on the frame 14 of said cutting mechanism between said turntable and the motor 15. The elevating mechanism disclosed herein is much the same as that employed in my prior Patent No. 2,082,119, excepting that in the present disclosure the upright frame members 12, 12, along which the cutting mechanism is vertically adjusted, are mounted directly on the base frame 10 instead of on a turntable.

In the form shown herein, a bevel pinion 80 is fixed on the end of the armature pinion, and is meshed with opposed bevel gears 81, 82, rotatably mounted on transverse shaft 83 and forming part of a reversing mechanism of the usual form, including a clutch member 84 feathered on shaft 83 and selectively engageable with the bevel gears 81, 82. The bevel gear 81 has a gear 85 integral therewith which is meshed with a gear 86 loosely mounted on a cross shaft 87. The bevel gear 82 has a gear 88 integral therewith which is meshed with a gear 89 loosely mounted on cross shaft 87. The gears 86 and 89 can be selectively engaged with cross shaft 87 to drive the latter in either direction by a clutch member 90 feathered on the latter shaft.

The cross shaft 87 has worms 91, 91 at opposite ends thereof, meshing with worm gears 92, 92 on longitudinal shafts 93, 93 journaled in pro-

jecting guide members 94, 94 at opposite sides of the frame 14. Said guide members have vertical engagement in grooves 95, 95 formed in the upright frame members 12, 12. At the outer ends of each shaft 93 are pinions 96, 96 engaging racks 97, 97 on the upright frame members 12. With the gearing just described, the entire cutting mechanism 13, including frame 14, motor 15, and turntable 11, can be raised or lowered by power relative to the upright frame members 12, 12, as desired.

The gearing for swinging the turntable 11 and feeding the cutter bars laterally comprises a gear 100 mounted on transverse shaft 83, which, as has been previously described, can be driven by the motor 15 in reverse directions. The gear 100 is meshed with gear 101 of a planetary gear reduction device indicated generally at 102. Said planetary is of the well known multiple speed, frictionally controlled type often used in mining machine feeds, and need not be described in detail herein. The driven member 103 of said planetary is feathered on a transverse shaft 104 having a worm 105 thereon meshed with a worm gear 106, rotatably mounted in a bearing support 107 and surrounding an upright shaft 108.

The gear 106 may be selectively engaged with the shaft 108 by a sliding clutch member 109. The shaft 108 has drive pinion 110 fixed to its upper end, which is meshed with the turntable gear 28. The gearing arrangement is such that the turntable 11 can be swung in either direction at a plurality of speeds, including a relatively slow feeding speed, through the frictionally controlled planetary 102.

The machine as a whole may be transported and operated over the mine tracks and the cutter bars can be fed by movement of the wheeled truck above the tracks, effected either by the truck wheels 23 and 25 driven from a motor 111 in the usual manner, not shown, or by means of a suitable rope feed, not shown; or the cutter bars may be fed by swinging the turntable so that said cutter bars effect an arcuate cut across the front of the machine.

It will be observed that the arrangement whereby the upright frame members 12, 12 are mounted directly on the base frame 10, and the cutting mechanism 13 including the turntable 11 has vertical adjustment as a whole along said guide frames, affords an especially low-height construction, because the turntable 11 is disposed generally in the same horizontal planes as the frame 14 and is vertically adjustable with the latter along the guide frames 12, instead of being interposed between the guide frames and the base frame to support the latter, as in previous constructions. Moreover, the arrangement whereby the turntable drive gear 28 is of relatively large diameter and is disposed adjacent the top of the machine in substantial alignment with the cutter bars, so as to reinforce the cutter bar support 35 and apply the turning movement directly to said cutter bars, affords an especially strong and efficient construction for machines of this type.

While I have herein shown and described one form in which my invention may be embodied, it will be understood that the construction thereof and the arrangement of the various parts may be altered without departing from the spirit and scope thereof. Furthermore, I do not wish to be construed as limiting my invention to the specific embodiment illustrated, excepting as it may be limited in the appended claims.

I claim as my invention:

1. In a mining machine, a base frame having a plurality of widely spaced upright supports thereon, a frame vertically adjustable between said upright supports, a turntable rotatably mounted at the forward end of said frame and having an arcuate driving member around its rear end, power means on said frame engaged with said driving member for swinging said turntable reversely, and a horizontally projecting cutter bar supported on the front of said turntable in substantially the same horizontal plane as said driving member.
2. In a mining machine, a wheeled truck having a base frame, and a plurality of widely spaced upright supports thereon, a supporting frame vertically adjustable relative to said upright supports, a horizontal turntable rotatably mounted on said supporting frame and having a centrally disposed cuttings discharge opening therein, a cutter bar having a cutter chain movable thereabout supported on said turntable with said cutter chain so disposed as to deliver the cuttings to said cuttings discharge opening, and conveyer means on said base frame beneath said cuttings discharge opening for carrying the cuttings rearward of said base frame.
3. In a mining machine, a wheeled truck, a conveyer extending along said truck, a plurality of widely spaced supports mounted on said truck, a supporting frame vertically adjustable between said supports, a turntable rotatably mounted on said supporting frame, and having a centrally disposed cuttings discharge opening therein communicating with said conveyer, and a radially extending trough in its periphery communicating with said discharge opening, and a chain carrying cutter bar supported in said trough with its rear end over said cuttings discharge opening.
4. In a mining machine, a wheeled truck, a conveyer extending along said truck, a plurality of widely spaced supports mounted on said truck, a supporting frame vertically adjustable between said supports, a turntable rotatably mounted on said supporting frame and having a centrally disposed opening therein forming a cuttings discharge passage communicating with said conveyer, a horizontally disposed cutter bar supported on said turntable and having a cutter chain movable thereabout, a sprocket for said cutter chain disposed coaxially with said turntable at the rear end of said cutter bar, and a motor on said supporting frame, and gearing supported on said supporting frame below said turntable and extending upwardly through the latter, affording operative connection between said motor and said cutter chain sprocket.
5. In a mining machine, a wheeled truck, a conveyer extending along said truck, a plurality of widely spaced supports mounted on said truck, a supporting frame vertically adjustable between said supports, a turntable rotatably mounted on said supporting frame and having a centrally disposed opening therein forming a cuttings discharge passage communicating with said conveyer, a horizontally disposed cutter bar supported on said turntable and having a cutter chain thereabout, a sprocket for said cutter chain at the rear end of said cutter bar disposed coaxially with said turntable, a motor on said supporting frame, and drive connections between said motor and said cutter chain sprocket including gearing housed in a portion of said supporting frame disposed between said turntable and said conveyer.

6. In a mining machine, a frame, a conveyer extending along said frame, a turntable supported at the front end of said frame above said conveyer, said turntable having an axially disposed cuttings discharge opening therethrough, and a radially extending trough in its periphery communicating with said discharge opening, a

5 horizontally disposed, chain-carrying cutter bar having its rear end supported in said trough and having its chain drive sprocket mounted coaxially of said discharge opening so that the cuttings will drop directly upon said conveyer from the rear and sides of said drive sprocket.

THOMAS E. PRAY.
